UNITED STATES PATENT OFFICE.

ORRIN R. STROME, OF PLEASANT DALE, SASKATCHEWAN, CANADA.

CLUTCH AND CHANGE-SPEED MECHANISM.

1,374,039.

Specification of Letters Patent.

Patented Apr. 5, 1921.

Application filed December 1, 1919. Serial No. 341,824.

To all whom it may concern:

Be it known that I, ORRIN R. STROME, a citizen of the United States, residing at Pleasant Dale, in the Province of Saskatchewan, Dominion of Canada, have invented certain new and useful Improvements in Clutch and Change-Speed Mechanism; and I do hereby declare the following to be a full, clear, and exact description 10 of the invention, such as will enable others skilled in the art to which it appertains to make and use the same.

This invention relates to power transmitting mechanisms, and has for its object 15 to provide a mechanism operating upon the principle of friction, by means of which power may be transmitted from a drive shaft to a driven shaft; by means of which the driving connection may be severed at 20 times; and by means of which the relative speed of the two shafts may be gradually varied from a one-to-one ratio, in either direction.

Another object is to provide a structure 25 which will be relatively simple and compact.

In the drawings:

Figure 1 is an elevational view partly in section, partly broken away, and partly in dotted lines illustrating the present invention.

Fig. 2 is a view similarly illustrative of the structure, the parts being shown in top plan.

Fig. 3 is a detail view partly broken 35 away and partly in section, showing one of the rolls in elevation.

Fig. 4 is a detail section through the transverse shaft and the movable sleeve which is splined thereon.

The present invention includes generally 40 a pair of opposed friction disks indicated in the drawings at 18 and 19 which disks are shiftable toward and away from each other as will be later explained, this shifting movement of the disks being provided in order that they may be brought into and out of contact with a pair of friction rolls indicated at 22 and 22' in the drawings. These rolls are mounted for movement diametrically of the disks, and means is provided 45 for moving them in unison, the structure being such that when one roll is shifted toward the periphery of the disks the other roll is shifted toward their centers. One 50 of the rolls is carried by a drive shaft indicated at 24 while the other is carried by

a driven shaft indicated at 23, and since, as will be seen from the drawings, the friction roll of the drive shaft imparts rotation to the disks which in turn impart rotation to the roll of the driven shaft, the structure provides for gradual variation of the relative speed of the drive and driven shafts from a one-to-one ratio in either direction.

Having given the above general statement of structure, operation and purpose, the accompanying drawings will now be referred to in detail.

The invention consists of a rectangular 70 casing including end walls 7 and 8, side walls 9 and 10 and top and bottom walls each indicated at 6. Mounted transversely of the casing and extending outwardly beyond the side walls 9 and 10 there is a shaft 75 11, the outer ends of which are mounted in supporting and bearing members 12, the shaft being engaged within openings 13' in the walls 9 and 10.

Engaged upon the shaft 11 and lying one 80 in each of the openings 13' there are slideable sleeves 13 and 13^a, the sleeve 13 being splined upon the shaft 11 as illustrated in Fig. 4. These sleeves 13 and 13^a carry respectively the disks 18 and 19, these disks 85 being located within the casing but having portions thereof projecting outwardly of the casing through suitable slots indicated at Z. A collar B is engaged with each of the sleeves 13 and 13^a for rotation of the 90 sleeve with respect thereto but for movement of the sleeve through movement of the collar, and toggle link mechanism indicated at 14 is connected with each collar and with the adjacent bearing member 12 95 as clearly shown in Fig. 2. Suitable levers C are connected by means of links C' with the toggle link mechanisms and these levers C are connected through the medium of links 15 with a yoke 16, which, in turn, is connected through the medium of a ball-and-socket D and links E with a hand lever 17 shown best in Fig. 1. The structure is thus such that when the hand lever 17 is moved in one direction the resultant operation of the link mechanisms 14 shifts the sleeves 13 and 13^a inwardly and moves the disks 18 and 19 toward each other, movement of the hand lever in the opposite direction separating the disks.

As set forth in the general statement of structure and operation, the friction rolls

22 and 22' are located between the disks and rest upon the shafts 23 and 24, the former being the driven shaft while the latter is the drive shaft. These shafts are mounted at 5 their inner ends in a web 20 located centrally of the casing 5 and serving also as a central bearing for the shaft 11 as shown very clearly in Fig. 1. The rolls are splined upon their respective shafts for sliding 10 movement longitudinally thereof and for rotation therewith, as will be understood.

For movement of the two rolls 22 and 22' in unison, there is provided a structure which includes two cross members 28, one 15 for each roll, these cross members including collars 27 engaged in circumscribing grooves 26 formed in hub extensions 25 of the rolls. The ends of these cross members are provided with heads 32 which are slidably 20 engaged in slots 31 formed in the top and bottom walls 6 of the casing, and the two cross members 28 are connected by longitudinal rods 29 slidably engaged in guideways 30 formed in the web 20. A hand lever 33 is connected with one of the cross members 28 by suitable linkage indicated at F and it will thus be apparent that when the hand lever 33 is moved in one direction 25 the roll 22 will be shifted inwardly toward the centers of the disks 18 and 19 while the roll 22' is shifted outwardly toward the 30 peripheries of the disks.

In the operation of the structure, the drive shaft 24 is rotated and carries the roll 35 22' therewith. The disks 18 and 19 having previously been brought into contact with the two rolls, these disks are rotated by the roll 22' and they, in turn, impart rotation to the roll 22 which carries the driven shaft 40 23 therewith. If the rolls 22 and 22' are equi-distant from the centers of the disks 18 and 19, a one-to-one ratio between the shafts 23 and 24 is established. If the roll 22 be shifted outwardly with resultant in- 45 ward movement of the roll 22', the speed of the shaft 23 is increased, while if the roll 22 be moved inwardly while the roll 22' is moved outwardly the speed of the shaft 23 is reduced.

50 A special advantage of the present construction lies in the fact that by reason of the arrangement of parts a very compact mechanism may be produced. This advantage results from connecting the two rolls 55 22 and 22' for movement thereof in unison since inward movement of the roll 22' re-

sults in rotation of the disks 18 and 19 at a greater speed with relation to the speed of the shaft 24 while the corresponding outward movement of the roll 22 results in its rotation at a greater speed with respect to the speed of rotation of the disks. Thus, but a slight movement of the rolls in either direction results in a considerable change of the gear ratio between the two shafts 60 23 and 24.

It will of course be understood that operation of the lever 17 to shift the disks 18 and 19 out of contact with the rolls 22 and 22' disconnects the two shafts 23 and 70 24 absolutely from each other so that the shaft 24 may rotate freely without imparting rotation to the shaft 23.

If desired, the shaft 11 may be provided with an extension at one end as indicated at X so that power may be taken from this shaft as well as from the shaft 23.

It will be understood, furthermore, that while the present invention has been described as mounted with the disks 18 and 80 19 lying in vertical planes, they may be disposed in any desired plane without affecting the operation of the mechanism.

In Fig. 1 there is illustrated at A a means for lubricating the bearings of the several 85 shafts which are formed by the web 20.

What is claimed is:

A mechanism of the class described including a casing having guideways therein, a web located in the casing, a shaft journaled in the casing and in the web, friction disks mounted upon the shafts for independent rotation, means for moving the friction disks toward each other, shafts journaled in the casing and in the web in alignment with each other, friction rolls 90 slidably mounted upon the aligned shafts for rotation therewith, a shifting frame connected with both of the rolls for movement of the rolls upon their shafts, guide 95 heads carried by the shifting frame and arranged to work in the guideways, said web having guideways therein, said shifting frame being slidably engaged in the guideways of the web, and means for moving the 100 shifting frame.

In testimony whereof I affix my signature in the presence of two witnesses.

ORRIN R. STROME.
